UNITED STATES PATENT OFFICE.

PRINCE SMITH, JR., OF KEIGHLEY, ENGLAND.

DOFFING MECHANISM FOR FLIER SPINNING, TWISTING, DOUBLING, AND ANALOGOUS MACHINES.

1,351,701.

Specification of Letters Patent. Patented Aug. 31, 1920.

Original application filed March 12, 1918, Serial No. 222,009. Divided and this application filed July 31, 1918. Serial No. 247,517.

To all whom it may concern:

Be it known that I, PRINCE SMITH, Jr., machine-maker, subject of the King of Great Britain, residing at Burlington Shed, 5 Keighley, Yorkshire, England, have invented certain new and useful Improvements in Doffing Mechanism for Flier Spinning, Twisting, Doubling, and Analogous Machines of which the following is a specification.

This invention relates to doffing mechanism for flier spinning, twisting, doubling and analogous machines, and has for its object to provide a simpler and more effective method of doffing than what has been employed previously.

This application is a division of my prior application filed March 12, 1918, Serial No. 222,009.

According to this invention the lifter plate with full bobbins is lowered on to a horizontally reciprocable rack which deposits the said lifter plate with full bobbins on to cam operated receiving means which 20 main stationary while another lifter plate with empty bobbins is placed in proper alinement so that it can be lifted up to the desired height for spinning.

The empty bobbins are positioned on another lifter plate which is adapted to rest on the horizontally reciprocable rack and behind the full bobbins in such a position that when the full bobbins are moved forward over the cam operated receiving 30 means, the empty bobbins are in proper alinement and ready to be lifted up to the spinning position.

The cam operated receiving means consist of a number of spindles slidably mounted in bearings and adapted to be operated by means of suitably shaped cams. The lower extremities of the spindles may be provided with anti-friction bowls.

The horizontally reciprocable bars are 40 recessed to receive the lifter plates.

The vertically reciprocable bars may be operated by means of racks and pinions, chains and pulleys or in any other suitable manner.

50 The invention will now be described with reference to the accompanying drawings

which show in side elevation the various positions of the doffing operation of one form of mechanism constructed in accordance with this invention.

Figure 1 shows the frame spinning with bobbins 2 full and ready for doffing and empty bobbins 3 with lifter plate 4 shown in the position occupied during spinning.

Fig. 2 shows the lifter plate 5 with full bobbins 2 lowered on to the racks 6 and said racks 6 moved forward, going with plates 5 and full bobbins 2 over the spindles 7 by operating the shaft 16 by means of a hand wheel on same.

This movement leaves the empty bobbins 3 and lifter plate 4 in their proper alinement and ready to be lifted up to spinning position.

Fig. 3 shows lifter plate 5 with full bobbins 2 lifted up to positions shown (viz: high enough to allow the rack 6 to return at its appointed time) by operating shaft 8 and cam 9.

Lifter plate 4 with empty bobbins 3 are 75 lifted up to spinning position by the ordinary lifter spindles or pokers and rack 6 returned to normal position and Fig. 4 shows the cutting apparatus 10 lifted up by operating shaft 11 in conjunction with 80 toothed wheels 12 and toothed racks 13 to position shown, in which position the threads 14 are severed after a few revolutions have been given to the fliers 15.

During the time the frame is spinning 85 and at the convenience of the operatives the full bobbins 2 are removed from plates 5 and replaced by empty ones.

What I claim is:—

Doffing mechanism for flier spinning, 90 twisting, doubling and analogous machines embodying a vertically movable lifter plate for carrying empty bobbins, a vertically movable lifter plate for carrying full bobbins, a horizontally reciprocable rack having a plurality of recesses for receiving said lifter plates, the lifter plate recess for the empty bobbins being disposed in the rear of the lifter plate recess for the full bobbins, and receiving means immovable at intervals 95 100 and vertically movable at other times for engaging and raising the lifter plate with

the full bobbins to permit the return move-
ment of said rack, said recesses being so
spaced that when the lifter plate with the
full bobbins is in operative position with
5 relation to said means the empty bobbins
are in proper alinement and ready to be ele-
vated to spinning position.

In testimony whereof I have hereunto set
my hand in presence of two subscribing wit-
nesses.

PRINCE SMITH, JR.
